HOT-AIR REGISTER

Bayre Levin, Detroit, Mich.

Application January 5, 1950, Serial No. 136,899

4 Claims. (Cl. 98—114)

1

This invention relates to hot air registers, and more particularly to a floor register construction.

Heretofore in the use of metallic floor registers there has been the disadvantage of their heating up from the hot air which is directed therethrough, and in some instances people have been burned by contact with such registers.

It is the principal object of this invention to provide a floor register which will not heat up excessively, and this is accomplished by a floor register construction which includes an intermediate hot air insulating pad or plate, whereby the grill of said register will not attain a dangerously high temperature. This and other objects will appear from the following specification and claims in conjunction with the appended drawing in which:

Figure 1 is a plan-view of the present floor register construction.

Figure 2 is a section on line 2—2 of Fig. 1.

Figure 3 is a fragmentary section on line 3—3 of Fig. 2.

Figure 4 is a fragmentary section on line 4—4 of Fig. 2, and

Figure 5 is similar to Figure 2, being a variation thereof.

It will be understood that the above drawing illustrates merely a preferred embodiment of the invention and that other embodiments are contemplated within the scope of the claims hereafter set out.

Referring to the drawing a floor is fragmentarily indicated at 11 with sub-flooring shown at 12. Rectangular opening 13 is formed through sub-flooring 12 and partially into the floor 11. Enlarged rectangular 14 is formed within the top portion of floor 11 at the upper end of opening 13.

Rectangular hollow frame 15 for the floor register is positioned through floor opening 13, said frame having a peripheral flange 16 which is cooperatively received within the floor opening 14 so that the top surface of said flange is in alignment with the floor 11.

The flange 16 projects from the upper portion of the register frame 15, and a second inwardly projecting flange 17 extends from the lower portion of said frame as shown in Figure 2, defining the central air opening 18.

A suitable preferably rectangular lower grill 19 with transverse perforations 20 is positioned within frame 15 and supported upon the flange 17, as indicated in Figures 2 and 4. The grill 19 is preferably metallic, however, it is contemplated that any other suitable material could be employed for this purpose.

2

Mounted upon the lower grill 19 within the frame 15 is a rectangularly shaped plate or pad 21 constructed of a heat insulating material, said plate being similarly perforated at 22, and with the perforations 22 being in substantial alignment with the perforations 20 of the grill 19. While a relatively large perforation 20 and 22 is shown, it is contemplated that the perforations may be of any desirable shape or size. Preferably, however, the perforations 20 of grill 19 should be in substantial alignment with the perforations 22 of the insulator pad 21 as shown in Figure 2.

A top or cover grill 23 is mounted upon insulator pad 21 within the frame 15, said grill also having formed therethrough a plurality of transverse perforations or openings 24, which are arranged in substantial alignment with openings 20 and 22, above described. The exterior dimensions of the top grill 23 are such that said grill is snugly or tightly received within the central opening of the register frame 15. Furthermore, the grills 19 and 23, as well as the insulator 21, are of such thickness that the top surface of grill 23 will be flush with the floor surface 11.

It is contemplated however that the top grill 23 could be otherwise secured to the frame 15, such as by a series of screws.

A ceiling furnace 25 of the hot air type is shown in dotted lines in Figure 2 being suspended from the ceiling 12 by a plurality of brackets 26 secured to said ceiling by the screws or bolts 27. This represents one type of hot air source such as may be used in basementless homes, or in house constructions where it is desired to suspend the hot air furnace from the ceiling of the basement. In any event, the particular hot air source, whether suspended as shown, or mounted upon the basement floor, as a hot air delivery pipe 28, which is adapted for communication with the inlet opening 18 formed within the register frame 15, so that the hot air is supplied to said register.

It has been found that heretofore the hot air heats up the register grill to such a point as to be dangerous to humans or animals, and it is therefore primarily the object herein to provide a hot air insulating medium within the floor register so that the top grill will not attain such dangerous temperature. The grill 23 is preferably metallic to support the weight of an individual, however, it is contemplated that other materials could be employed which would have such rigidity.

The present embodiment shows the lower grill

19 which acts as a support for the insulator 21. It is contemplated that this grill could be omitted if desired, and still attain the object above set out. However, it is apparent that this lower grill acts as a further support for the insulator pad.

As shown in Figure 1, the register frame 15 is immovably secured within the floor openings by a plurality of screws 29 which extend downwardly through openings in the flange 16 and into the floor 11.

While a rectangular frame is shown it is naturally contemplated that such frame could be of any desired shape, such as circular.

Fig. 5 is similar to Figure 2 but represents a slight variation in the construction of the register. A hollow rectangular frame 15' is shown similar to the frame 15 of Figure 2, however, it is apparent that said frame is not quite as deep.

A peripheral flange is also provided at the upper end of the frame for supporting said frame in exactly the same manner shown in Fig. 2. Similarly at the lower end of frame 15' there is also an inwardly extending flange upon which it is supported and secured the body of said register. The latter includes a plurality of parallel spaced metallic tubular elements 30 whose opposite ends extend over the interior inwardly extending lower flange of frame 15'.

One or more reinforcing crossbars 31 are arranged below and transversely of the length of the tubes 30 with the respective opposite ends of said crossbars overlying portions of the inwardly extending flange of said frame as shown in Figure 5. Said crossbars may be secured to the tubular elements 30 in any suitable manner such as by welding at points 33, to thereby provide a unitary and rigid structure.

While in Figures 1 through 4 there is shown a separate heat insulating plate or pad 21 it is contemplated in the variation shown in Figure 5 that the respective tubes 30 be filled with a suitable, preferably non-metallic, heat insulating substance 32, to thereby render the tubes 30 substantially less heat conductive.

Having described my invention reference should now be had to the claims which follow for determining the scope thereof.

I claim:

1. In a hot air register for a floor having an opening in communication with a hot air source, a hollow frame in said opening, a peripheral flange around the upper portion of said frame supportably engageable with said floor, an inwardly projecting flange within the lower portion of said frame, a perforated plate constructed

of a heat-insulating substance positioned within said frame and supported upon said inwardly projecting flange, and a similarly perforated metallic grill positioned within said frame and supported upon said plate.

2. In a hot air register for a floor having an opening in communication with a hot air source, a hollow frame in said opening, a peripheral flange around the upper portion of said frame supportably engageable with said floor, an inwardly projecting flange within the lower portion of said frame, a perforated metallic grill within said frame supported upon said latter flange, a perforated plate constructed of a heat-insulating substance positioned within said frame and supported upon said grill, and a similarly perforated metallic grill positioned within said frame and supported upon said perforated plate.

3. In a hot air register for a floor, a pair of parallel spaced perforated metallic grills, and a similarly perforated pad constructed of a heat-insulating material interposed between and engaging said grills, with all said perforations being in substantial alignment.

4. In combination, a floor having an opening therethrough, a hot air source suspended from the under side of said floor adapted to deliver a flow of hot air through said opening, and a register within said opening consisting of a supporting frame with a peripheral flange positioned within said opening and with said flange engaging said floor, an inwardly-extending flange on said frame, a pair of spaced perforated metallic grills within said frame, upon said latter flange, and a similarly perforated pad of heat-insulating material interposed between said grills.

BAYRE LEVIN.
